UNITED STATES PATENT OFFICE.

ALLEN D. BLODGETT, OF LOS ANGELES, CALIFORNIA.

MECHANICAL MOVEMENT.

1,183,795.

Specification of Letters Patent. Patented May 16, 1916.

Application filed October 23, 1915. Serial No. 57,611.

To all whom it may concern:

Be it known that I, ALLEN D. BLODGETT, a citizen of the United States, residing at Los Angeles, in the county of Los Angeles and State of California, have invented a new and useful Mechanical Movement, of which the following is a specification.

My invention relates to mechanical movements, and the principal object of my invention is to produce a mechanical movement which is especially adapted to operate the valves of a four stroke cycle internal combustion engine. This mechanical movement may, however, be used for any purpose 10 where similar results are desired.

In a four stroke cycle gas engine it is necessary to lift each of the exhaust and intake valves once in each two revolutions of the crank shaft, and it is further necessary that 20 the valve be lifted quickly and allowed to seat quickly if the best results are to be obtained.

It is common practice in the gas engine art to provide an auxiliary cam shaft which 25 is operated by means of timing gears from the crank shaft so that it rotates once for each two rotations of the crank shaft, cams being secured to this cam shaft for operating the valves. In my invention no auxiliary cam shaft is necessary, eccentrics being 30 turned directly on the crank shaft, these eccentrics operating the valves at their proper time without the necessity for timing gears or equivalent structure.

35 In the drawings, which are for illustrative purposes only: Figure 1 is a somewhat diagrammatic vertical section through a portion of an internal combustion engine equipped with my invention. Fig. 2 is an 40 enlarged section showing the method of applying the mechanical movement thereto. Fig. 3 is a section on a plane represented by the line x^3-x^3 of Fig. 2, looking in the direction of the arrows.

45 In this form and application of my invention, a crank shaft 11 is provided turning freely in bearings 12 formed on a crank case 13. A cylinder casing 14 is secured to the crank case 13. A piston 15 slides in the

cylinder casing 14 having a connecting rod 50 16 pivoted thereon. The connecting rod 16 engages a crank 17, this crank being carried between arms 18 having eccentrics 19 turned thereon. Turning freely on the eccentrics 19 are eccentric straps 20, each of which has a 55 cylindrical portion 21 fitting tightly around the eccentrics 19. Cut in the outside of the eccentric projection 21 are working openings 22 and 23 and clearance openings 24 and 25. Secured to the side of the crank case 13 are 60 finger plates 26, these plates being duplicates of each other, and each having secured thereon a series of five fingers 27, 28, 29, 30 and 31, these fingers being radial with respect to the axis of the crank shaft 11 and 65 being disposed equally distant around the circle, the center line of each of them making an angle of 72 degrees with the center line of the adjacent finger. The proportions of the above parts must follow the following rule if the parts are to operate successfully together, the center of the crank shaft being denoted by the letter O, and the center of the eccentric being denoted by the letter E. Radial lines O—A and O—B are 70 drawn through the center of the fingers 28 and 30, and a line C—D is drawn at right angles to the line E—O connecting the centers mentioned above. The intersection of the line O—B and the line C—D or X determines the outside diameter of the eccentric strap 20. The working openings 23 have a width M equal to the width M of 75 each of the fingers 27, 28, 29, 30 and 31, being cut away on the inner side to give a 80 clearance to these fingers as the strap turns. Formed on the eccentric strap 20 are cam members 32 and 320, these cam members being diametrically opposite each other, extending out a distance L from the outer 85 edge of the eccentric strap 21 in such a position that they engage and operate the valve stem 33, this valve stem extending upwardly and operating the valves of the engine through means not shown. By variations in the dimensions L the time the valve 90 33 is kept open on the intake and exhaust strokes can be controlled.

The method of operation of the invention is as follows: The rotation of the crank shaft 11 being in the direction of the arrow 40, shown in Fig. 3, the working opening 22 being engaged by the finger 29, the fingers 28 and 30 are in the clearance openings 24 and 25, and the fingers 27 and 31 are entirely free and disengaged. As the eccentric 19 rotates, it forces the opening 23 to the right and downward, as seen in Fig. 3, until the finger 27 enters the opening 23. After the opening 23 has been engaged by the finger 27, the opening 22 is disengaged from the finger 29 and the opening 23 slides in the direction of the arrow 41 until the line O—E coincides with the radial line O—F, passing through the finger 27. Further rotation of the eccentric 19 causes the opening 22 to engage the finger 30.

20 The cycle of operations for four revolutions of the eccentric 19 is as follows: Starting with the opening 22 engaged by the finger 29, the opening 23 is engaged by the finger 27, the opening 22 is engaged by the finger 30, the opening 23 is engaged by the finger 28, the opening 22 is engaged by the finger 31, the opening 23 is engaged by the finger 29, the opening 22 is engaged by the finger 27, the opening 23 is engaged by the finger 30, the opening 22 is engaged by the finger 28, the opening 23 is engaged by the finger 31, and the opening 22 is engaged by the finger 29, returning the parts to their original position. While the eccentric 19 rotates four times in the direction of the arrow 40, the eccentric 20 rotates once in the opposite direction to the arrow 40, so that the cam 32 operates the valve 33 once in every four revolutions of the crank shaft, 40 and the cam 320 operates the valve 33 once every four revolutions of the crank shaft. The result is that the valve 33 is lifted once every two revolutions, or once every four strokes of the piston, this being the desired 45 result to operate the valves of a four stroke cycle engine. The dotted line 50 of Fig. 3 indicates the path which a point 51 on the center of the face of the cam 32 follows during four revolutions of the crank shaft 11.

50 It is to be noted that the approach of the cam 32 toward the valve stem 33 and the recession therefrom is very rapid so that the valve is lifted positively and quickly.

Considered strictly as a mechanical movement certain obvious changes can be made in this invention without altering the principle upon which it works, or the real relationship of the parts. For example, the plate 26 may be called a primary member, 55 and the eccentric strap 20 may be called the secondary member. The shaft 11 and the eccentric 19 are for a single purpose, *i. e.*, the actuation of the secondary member eccentrically with relation to the primary mem-

ber, and might be called the actuating means. Obviously a crank might be used in either the primary or the secondary member without changing the essential nature of the actuating means. The fingers 27, 28, 29, 30 and 31 might be called radial arms, and 70 walls forming the slots 22 and 23 might be called engaging members. In the drawing the radial arms are projections, and the engaging members are the walls of slots. A reversal of this feature by substituting slots 75 for the fingers, and projections for the slots 22 and 23 is also obviously within the spirit 80 of my invention.

I claim as my invention:—

1. A mechanical movement comprising a 80 stationary support, a shaft turning freely in said support, an eccentric secured to said shaft, an eccentric strap turning freely on said eccentric and having a pair of working openings formed 180° apart therein, a series 85 of projections on said support so placed that they engage working openings and rotate said eccentric strap as the shaft is turned, a valve stem, and means on said eccentric strap for lifting said valve stem. 90

2. A mechanical movement comprising a stationary support, a shaft turning freely in said support, an eccentric secured to said shaft, an eccentric strap turning freely on said eccentric and having a pair of working openings formed 180° apart therein, a series 95 of radial fingers secured equally distant around said support in such a position that they engage and turn said eccentric strap as said shaft turns, a valve stem, and means on 100 said eccentric strap for lifting said valve stem.

3. A mechanical movement comprising a stationary support, a shaft turning freely in said support, an eccentric secured to said shaft, an eccentric strap turning freely on said eccentric and having a pair of working openings formed 180° apart therein, a series 105 of five radial fingers secured equally distant around said support in such a position that they engage and turn said eccentric strap as said shaft turns, a valve stem, and means on 110 said eccentric strap for lifting said valve stem.

4. A mechanical movement comprising a 115 primary member, a secondary member, means for causing one of these members to move eccentrically with relation to the other, radial structure on the primary or the secondary member, engaging structure on the other member so placed as to rotate one of said members with relation to the other, a valve stem fixed with relation to one of said members, and means on the other member for lifting said valve stem. 120

5. A mechanical movement comprising a primary member, a secondary member, means for causing one of these members to

move eccentrically with relation to the other, five radial engaging structures secured to one of said members at equal angular distances about its center, engaging 5 means on the other member said engaging means being located on diametrically opposite sides of the center of the said last named

member, a valve stem fixed with relation to one of said members, and means on the other member for lifting said valve stem. 10

In testimony whereof, I have hereunto set my hand at Los Angeles, California, this 18th day of October, 1915.

ALLEN D. BLODGETT.
